UNITED STATES PATENT OFFICE.

SCHOOLER C. HORN, OF BLADENSBURG, OHIO.

COMBINED STORM-COAT AND VEHICLE-APRON.

SPECIFICATION forming part of Letters Patent No. 417,028, dated December 10, 1889.

Application filed September 9, 1889. Serial No. 323,376. (No model.)

To all whom it may concern:

Be it known that I, SCHOOLER C. HORN, of Bladensburg, in the county of Knox and State of Ohio, have invented a new and Improved 5 Storm-Coat and Vehicle-Apron Combined, of which the following is a full, clear, and exact description.

This invention has for its object the production of a garment or article which shall effectually protect the clothes or person of the 10 driver or other occupant of a buggy or other like vehicle from rain, snow, mud, and wind; and it consists in a combined storm-coat and vehicle-apron, with special attachments for 15 connecting it with the dash-board, and with specially-constructed sleeves for the arms and hands of the wearer, substantially as herein-after described, and pointed out in the claims.

Reference is to be had to the accompanying 20 drawings, forming a part of this specification, in which similar letters of reference indicate corresponding parts in all the figures.

Figure 1 represents a perspective view, as seen from the front, of the improved article 25 before being applied to the person of the wearer, a portion of one of the sleeves being broken away. Fig. 2 is a view in perspective of the same as seen from its back and when open. Fig. 3 is a transverse vertical section 30 of the dash-board of a vehicle in part, with the apron portion of the garment as secured thereon or thereover; and Fig. 4 is a view in perspective of a modified construction of the hook used to secure the apron portion of the 35 garment to the dash-board.

The garment or article is made of any suitable water-proof material with or without lining, including the body and sleeves. The body A is made open behind throughout its length, 40 fastening about the neck or upper portion of the person, as by buttons or otherwise, and is of a length to take in the whole person, and when in use to reach to or over the dash-board of the buggy. It thus presents a close front, 45 and its lower half or portion b constitutes, when extended to or over the dash-board of the vehicle, a buggy or vehicle apron. The sleeves of the garment are each composed of an upper and lower section B B', arranged to 50 telescope one into the other at a point or place between the elbow and shoulder, and the lower

part of the sleeve B', which is extended and constructed to form a glove or mitten, is attached to the upper sleeve-section B by longitudinally-arranged elastic cords or straps c, 55 united at their ends, as by sewing and hook-and-eye fastenings d, or otherwise, to the two sleeve-sections B B'. This construction of the sleeves provides for their adjustment to any length of arm, and as when the garment is in 60 use that portion of the arm between the elbow and shoulder is seldom or never raised above a horizontal position rain or snow will not penetrate at the junction of the two sleeve-sections, and by the construction of the sleeve 65 as described full protection is given to the arms, wrists, and hands, while the remainder of the person, from the neck downward, is similarly protected by the body of the garment or article against cold and bad weather. 70

The main body A of the garment is made in one continuous piece, and, as hereinbefore described, of a length to reach from the neck down to and over the dash-board C of the vehicle, its portion b, which forms the vehicle-apron, lapping over the dash-board and being secured to it by sliding spring-hooks D, attached to the apron portion b, thereby giving the person absolute protection against any kind of storm or bad weather, wind, and mud. 75 The spring-hooks or fastenings D are secured to the apron portion b by eyes or staples e, riveted securely to said apron portion at a sufficient distance from the lower or outer end of the combined garment and vehicle-apron 80 to allow of the portion b lapping over the dash-board, as shown in Fig. 3, and of being secured thereon by the spring fastenings or hooks D, regardless of the width of the dash-board, and doing away with the inconvenience 85 and expense of making perforations in the apron, as usual in other storm-aprons.

The spring-hooks D are made with a slotted shank portion f, which passes freely through the eyes or staples e. To attach the apron 90 portion b to the dash-board, its end is first thrown over said board, bringing the eyes e, through which the hooks slide, to or over the top of the dash-board, and the hooks being raised to their fullest extent in the eyes e. The 100 apron portion b is then drawn down on the inside of the dash-board until the hooks catch

over said board, after which the finger is applied to the top of the hooks and the latter pushed down firmly over or on the top of the dash-board, thereby clamping the apron portion *b* to its place on the board. To detach the apron portion *b* from the dash-board, it is only necessary to give an upward stroke to the hooks.

Fig. 4 of the drawings shows a modified construction of the hooks—that is to say, it shows a hook *D*, made of wire, doubled or bent to form two slotted shanks *f*, which pass through two staples or eyes *e*, secured to the apron portion of the garment.

Having thus fully described my invention, I claim as new and desire to secure by Letters Patent—

1. As a new article of manufacture, a vehicle-apron provided with telescoping sleeves having elastic connections connecting them with the apron, substantially as set forth.

2. As a new article of manufacture, a vehicle-apron provided on its outer side above its lower edge with clamps having a sliding connection with the apron in the direction of the length of said apron, substantially as set forth.

3. The combination, with the vehicle-apron, of eyes secured thereto and hook-shaped clamps provided with shanks sliding through said eyes, substantially as set forth.

4. The combination, with the vehicle-apron, of eyes secured thereto and hook-shaped clamps provided with looped or slotted shanks sliding through said eyes, substantially as set forth.

35

5. In a storm-protector, the combination, with the body of the article, having a neck-fastening at its upper end and short sleeve-sections *B* *B*, of the sleeve-sections *B'* *B'*, extending into the sections *B*, and having mittens or gloves at their lower ends and elastic strands *c*, secured to the inner ends of the sections *B'* and to the body, substantially as set forth.

40

6. In a combined storm-coat and vehicle-apron, the combination, with the body part *A*, made open in the rear and closing above about the person and of a length to form a vehicle-apron portion *b*, of the sleeves constructed of upper and lower telescoping sections *B* *B'*, united with each other by longitudinal elastic connections, and with the lower section *B'* constructed to form a glove or mitten cover for the hand, essentially as described.
